United States Patent Office

Des. 221,097
Patented July 6, 1971

221,097

HIBACHI

Joseph B. Stier, Brooklyn, N.Y., assignor to Styson Inc., New York, N.Y.

Filed May 14, 1970, Ser. No. 22,985

Term of patent 14 years

Int. Cl. D7—02

U.S. Cl. D44—1

Fig. 1.

Fig. 2.

FIG. 1 is a front elevational view of an hibachi showing my new design;

FIG. 2 is a top plan view;

FIG. 3 is a plan view on line 3—3 of FIG. 1; and
FIG. 4 is a plan view on line 4—4 of FIG. 1.

I claim:

The ornamental design for an hibachi, substantially as shown.
